UNITED STATES PATENT OFFICE

162,089

GAMEBOARD

Edward H. Schmidt, Baltimore, Md.

Application March 13, 1950, Serial No. 8,500

Term of patent 7 years

(Cl. D34—5)

To all whom it may concern:

Be it known that I, Edward H. Schmidt, a citizen of the United States, residing at Baltimore, State of Maryland, have invented a new, original, and ornamental Design for a Gameboard, of which the following is a specification, reference being had to the accompanying drawing, forming a part thereof.

In the drawing:

Fig. 2 is a transverse section on the line 2—2, Figure 1.

I claim:

The ornamental design for a gameboard, substantially as shown.

EDWARD H. SCHMIDT.
